UNITED STATES PATENT OFFICE.

GUSTAF SANFRID PAULL, OF GREENSBURG, PENNSYLVANIA.

CUFF-LINK.

1,243,547.

Specification of Letters Patent. Patented Oct. 16, 1917.

Application filed March 19, 1915. Serial No. 15,458.

To all whom it may concern:

Be it known that I, GUSTAF S. PAULL, a citizen of the United States, residing at Greensburg, in the county of Westmoreland and State of Pennsylvania, have invented certain new and useful Improvements in Cuff-Links, of which the following is a specification.

The invention has for an object to provide a new form of cuff button device which may be quickly applied or removed with ease, and which will be liable in a minimum degree to accidental disengagement. A further object is to provide button stud elements for engagement in respective sides of the cuff, with a novel and desirable resilient connection therefor having a peculiar co-operative relation to the cuff and the studs. It is a particular object to provide separate button elements and a connecting resilient member having the necessary play to permit manipulation of the device as desired, the resilient connection being so formed as to connect with the button elements outwardly of the cuff, and yet will not be prominent, but will have the necessary extended portions required for the degree of movement desired, arranged so as to go between the ends of the cuff.

Additional objects is to give such a device that may be cheaply constructed, and which may be ornamented, so that it will be attractive.

Additional objects, advantages and features of invention will appear from the construction, arrangement and combination of parts comprising two of the possible embodiments of my invention set forth hereinafter and illustrated in the drawings.

where,

Figure 1 is a bottom view of a cuff having my device engaged therewith,

Fig. 2 is a side view thereof,

Fig. 3 is a detail view of the fastener,

Fig. 4 is a detail of a modification of the device.

There is illustrated a cuff 10 of ordinary form, having button holes 11 at each end adjacent its lower or outer edge, in which there are engaged button studs 12, inserted from the outside, carried upon respective spring plates 13 of a resilient connecting element 14. The studs each comprises a shank 15 having a rounded head 16 at its outer end, its inner end being riveted or otherwise secured to the plate 13. The

heads do not require to be very large and are of such shape that they may be easily forced inwardly or outwardly through the button holes of the cuff. The plates 13 form integral parts of a spring element 17, which forms a connection between the plates. This spring element comprises two spring arms 18 tapered toward their inner ends and joined by an integral circular eye piece 19. The edges of the arms 18 curve outwardly from a point a short distance outwardly of this eye piece, until they reach the full width of the plates 13, the arms being planiform normally, until they attain this width. Their outer broad parts are then bent outwardly and then inwardly as at 20, to form the plates 13, these connecting portions being preferably curved as shown, and of such dimension as to space the plates outwardly of the planiform portions of the arms sufficiently to permit the free play of the end edges of a cuff on respective sides of the spring 17. The spring is under stress tending to force the heads of the studs 12 together, and the shanks of these studs are of such length as to hold the plates 13 approximately in parallel relation when the heads of the studs coengage.

The plates 13 and portions 20 are preferably sufficiently rigid to resist distortion by the normal action of the spring 17, and the plates may be ornamented in any desired fashion.

It will be apparent that the device is well adapted to be economically produced from stock materials ordinarily employed for such devices, and by customary shop methods.

In use, the device may be engaged with a cuff with the greatest ease. It is only necessary to press the edges of the cuff between the heads 16 with a sliding movement, either separately or together, until the button holes are engaged under the respective heads and then press the sides of the cuff outwardly adjacent the button holes until the studs become properly engaged. Removal of the fastener may be easily accomplished by pulling outwardly on first one plate 13 and then the other, while the adjacent side of the cuff is pressed inward. It will be noted that the arms 18 diverge in such a manner that the end portions of a cuff will be engaged and held outwardly a sufficient distance to prevent casual disengagement of the studs through the button holes.

In Fig. 4 there is shown a cross sectional

view in which it will be seen that the eye portion 19 is broadened, and that the arms are attenuated, their curved edges being slightly convergent for a short distance outwardly of the eye 19 and then divergent until they are broadened to the full width of the plates 13, as before mentioned. In this way the point of flexure of the spring is moved outwardly from the studs.

10 It is possible to remove the device by simply pressing on the outer end portions of the plates 13, which will cause a separation of the studs and permit ready disengagement of the fastener from the cuff. It should be noted that at the same time that the studs are separated by this manipulation, the inward movement of the outer parts of the plates 13 will press the ends of the cuff inward forcing them off the studs.

15 20 In Fig. 5 a modification is illustrated in which the stem 25 of the stud is stamped integrally from the body of the plate 13' and a suitable head 26 secured thereon.

The heads of the studs may be formed in

an oblong shape, with their major dimensional axis disposed to align with the button holes and their outer sides may be somewhat pointed as shown in Fig. 5 to facilitate their engagement through the button-holes.

30 What is claimed:

A cuff button comprising a body of resilient sheet metal attenuated at its intermediate part, bent at its middle to form divergent spring arms, the material of the body being abruptly recurved at the extremities of these arms and outwardly of said attenuated portions, to form cuff confining members, and headed stud elements upon the inner sides of the cuff confining members, the parts in said body being under tension tending to bear said studs together.

35 In testimony whereof I have affixed my signature in presence of two witnesses.

GUSTAF SANDFRID PAULI.
